CLAIM

The ornamental design for a foldable mobile phone, as shown and described.

DESCRIPTION

FIG. 1 is a front view of the foldable mobile phone in an unfolded state showing my new design.

FIG. 2 is a rear view of the foldable mobile phone of FIG. 1.

FIG. 3 is a left side view of the foldable mobile phone of FIG. 1.

FIG. 4 is a right side view of the foldable mobile phone of FIG. 1.

FIG. 5 is a top view of the foldable mobile phone of FIG. 1.

FIG. 6 is a bottom view of the foldable mobile phone of FIG. 1.

FIG. 7 is a left front perspective view of the foldable mobile phone of FIG. 1; and,

FIG. 8 is a top view of the foldable mobile phone of FIG. 1 in a folded state.

The shade lines in the figures show contour.

The broken lines that are immediately adjacent to the claimed design represent the bounds of the claimed design, while all other broken lines, showing the remainder of the foldable mobile phone, are directed to environment and are for illustrative purposes only; the broken lines form no part of the claimed design.

1 Claim, 6 Drawing Sheets
